FEEDING OR DRIVING MECHANISM

William F. Focha, Piedmont, Calif., assignor to
 Wailes Dove-Hermiston Corporation, New
 York, N. Y., a corporation of New York

Application December 9, 1933, Serial No. 701,663

17 Claims. (Cl. 242—11)

Statement of invention

My invention relates to a feeding or driving mechanism, and more particularly to a mechanism for imparting to a cylindrically shaped object, such as a pipe, a combined rotary and longitudinal movement. In a specific sense, the invention pertains to pipe wrapping machinery, whereby the pipe can be spirally wrapped as a result of the motion which my feeding or driving mechanism imparts to the pipe.

Introduction

Pipe wrapping machines of the kind imparting a combined rotary and longitudinal movement to the pipe, are generally of two classes. They are the roller drive machine and the belt drive machine. In the latter type of machine, a driven belt engages the pipe at a selected angle. It is extremely difficult to prevent the belt from wobbling and thereby imparting wobbling to the pipe. Furthermore, in the belt type of machine, there is always the problem of obtaining sufficient frictional engagement of the belt with the pipe. The roller type of machine generally comprises three or more radially disposed rollers adjustable to a selected angle. These rollers have arcs which are opposed to the arc of the pipe and, therefore, have only point contact with the pipe, which results more or less in wobbling of the pipe as the rollers are driven. On account of the limited point contact of each roller with the pipe, considerable pressure must be applied on the rollers to provide for traction. Because a drive must be imparted to the rollers which are angularly and radially adjustable, the driving mechanism and mounting of the rollers necessitate a complicated and expensive construction.

Objects of invention

The feeding or driving mechanism of my invention is of such construction as to obviate the disadvantages of the foregoing described types of machines.

It is an object of my invention to provide a driving or feeding mechanism for imparting a combined rotary and longitudinal movement to a cylindrically shaped object, and which is of an extremely simple and economical construction.

Another object of my invention is the provision of driving mechanism, of the character described, which engages the pipe over a relatively long arc to provide for a positive movement of the pipe without wobbling thereof, and to provide for a

large area of contact with the pipe thereby enhancing traction.

Another object of my invention is the provision of a driving mechanism in the form of annular means providing a pipe engaging arc extending in the same direction as the arc of the pipe.

Another object of my invention is the provision of driving mechanism, of the character described, which is adjustable to vary the feed of the pipe.

A further object of my invention is the provision of non-roller driving mechanism.

An additional object of my invention is the provision of a pipe wrapping machine of simple and economical construction.

My invention has for its objects numerous other features, which will become apparent from a perusal of the following description of the invention. In the description, the term "pipe" is meant to apply to any cylindrically shaped object as well as to pipes.

General description of invention

In general terms, the driving mechanism of my invention comprises annular means through which the pipe is adapted to pass, which is adjustable to be set at a selected angle with respect to the pipe and is also rotatable about its axis. Because of the angular setting of the annular means, the pipe is contacted over an extended arc disposed at an angle with respect to the longitudinal axis of the pipe; and as such annular means is rotated, the pipe is given a combined rotary and longitudinal movement. An important discovery which I have made is that if a ring through which a pipe extends, is disposed at an acute angle with respect to the axis of the pipe, it will contact the pipe over an extended arc, although it will have only a point contact with the pipe when the plane of the ring is disposed at a right angle to the axis of the pipe. If such ring is rotated while at any acute angle with respect to the axis of the pipe, the pipe will be given a combined rotary and longitudinal movement. Thus, the type of drive of my invention, in contradistinction to the roller type of drive, has an arc contact with the pipe to insure positive feeding of the pipe without wobbling.

The combined rotary and longitudinal movement of the pipe is utilized to effect unwinding from a roll of wrapping material set at a selected angle with respect to the pipe, of wrapping which is, consequently, wound helically about the pipe in the usual manner.

Description of drawings

Reference will now be made to the drawings for a more detailed description of a preferred embodiment of my invention; it being of course understood that the invention can assume numerous other embodiments as defined by the claims. In the drawings:

Figure 1 is a side elevation of a preferred machine of my invention.

Figure 2 is a plan view of the machine shown in Figure 1.

Figure 3 is a transverse vertical section taken in a plane indicated by line 3—3 of Figure 1.

Figure 4 is a longitudinal vertical section through the driving or pipe feeding mechanism.

Figure 5 is a fragmentary section taken in a plane indicated by line 5—5 of Figure 3.

Figure 6 is a plan view of a modified form of driving mechanism.

Figure 7 is a sectional side elevation of the structure shown in Figure 6, looking in the direction of arrow 7 shown in Figure 6.

Figure 8 is an end elevation of another modified driving mechanism.

Figure 9 is section taken at line 9—9 of Figure 8.

Figure 10 is a fragmentary section of a still further modified form of driving mechanism.

Detailed description

With reference to Figures 1 and 2, a preferred form of apparatus of my invention, in the form particularly adapted for wrapping of pipe, comprises driving mechanism, indicated generally by reference character 1, for imparting a combined rotary and longitudinal movement to pipe 2, which can be suitably supported adjacent its ends, in addition to the support provided by the driving mechanism hereinafter described.

The combined rotary and longitudinal movement of the pipe is utilized to effect spiral wrapping, in the usual manner, of material such as roofing felt, from a roll 3 thereof. Roll 3 is mounted on table 4 adapted to move over arcuate trackway 6 having a true radial curvature, the center of which is determined by a point directly under the longitudinal axis of pipe 2. Thus, table 4 can be moved over trackway 6 to a position which will cause feeding of the wrapping strip 7 in the proper direction. Trackway 6 is joined to a side of tank 8 which contains suitable adhesive material, such as hot bitumen, for uniting the wrapping to the pipe. In order to provide for final adjustment of the roll 3, so as to have the proper lead off angle of strip 7 to the pipe, an adjustable connection is utilized. The connection comprises threaded rod 9 connected to table 4 and screw threaded in bracket 11 secured to trackway 6; the rod 9 being held in adjusted position by means of lock nut 12. Suitable strip tensioning means 13 is provided, to insure that the wrapping strip feeds to the pipe without any slack therein.

As the pipe is fed forwardly with a rotary motion by the feed mechanism 1, the wrapping strip 7 winds helically about the pipe from roll 3; the angle of feed of strip 7 and the movement relationship of pipe 2 being such as to cause overlapping of the strip convolutions on the pipe, thereby causing the entire pipe to be covered.

For applying the adhesive material in tank 8, onto the wrapping, a pump 14 is provided in tank 8. The pump discharges the adhesive fluid into conduit 16 having curved upper neck 17 which

directs the adhesive onto the strip 7 adjacent the line of contact of the strip with the pipe, as is shown more clearly in Figure 2. Pump 14 is driven from Reeves drive 18 by means of shaft 19, chain 21 and shaft 22; the Reeves drive being in turn driven by suitable prime mover 23.

The preferred construction of my feed or drive mechanism 1 will now be described; it being understood that such mechanism can be employed for imparting a combined rotary and longitudinal movement to any cylindrically shaped object, although it is of particular applicability in a pipe wrapping machine. Such feed mechanism (Figs. 1 thru 5) comprises an annular split frame which includes lower semi-cylindrical, U-shaped section 31 to which is detachably secured upper semi-cylindrical, U-shaped section 32, by means of mating flanges 33 at the ends of said sections and suitable fastening means 34 extending through the flanges. Lower section 31 (Fig. 4) has cylindrically shaped boss 36 journaled for rotation in support 37 secured on frame 38 (Figs. 1 and 2). Thus, the annular split frame 31, 32 is mounted for angular adjustment about an upright axis perpendicular to the axis of the pipe (Fig. 3).

Journalized for rotation in annular frame 31, 32 by means of rollers 39 mounted in the frame, is a driving ring 41 (Figs. 4 and 5) having spaced peripheral flanges 42 contacting rollers 39. The driving ring can be readily positioned when the frame sections 31 and 32 are detached; and upon securing together of sections 31 and 32, driving ring 41 is securely held in place. A detachable annular section 43, for a purpose to be subsequently described, is provided for the driving ring 41; the section being secured to inwardly projecting annular flange 44 on part 41, by means of fastening bolts 46.

Rotation of the driving ring in split frame 31, 32 is effected by means including vertical shaft 40 47 (Fig. 4) passing through boss 36 of lower frame sections 31 and journaled in bushings 48. On the upper end of shaft 47 is secured a driving pinion 49 meshing with gear teeth 51 formed on the inside of one of ring flanges 42. A bevel gear 52 is secured on the projecting lower end of shaft 47, and meshes with bevel pinion 53 (Fig. 1) on shaft 54 driven from Reeves drive 18. It is thus seen that rotation of shaft 47 results in rotation of the annular driving means for the pipe. The axis of shaft 47 is the axis about which split frame 31, 32 can be angularly adjusted, by virtue of the journal mounting which boss 36 provides. As a result, the angular adjustment can be effected without disturbing in any manner the driving connection.

Means is provided to effect angular adjustment of the driving mechanism with respect to the axis of the pipe. A bracket 57 (Figs. 1 and 3) is provided on lower frame section 31, in which is pivotally mounted threaded rod 58 having screw threaded thereon hub 59 of hand-wheel 61. Hub 59 is journaled and held against axial movement in bracket 62 secured to support 37. Turning of hand-wheel 61 will, hence, result in angular movement of split frame 31, 32 together with the driving ring therein, about the upright axis of drive shaft 47.

In operation, the pipe extends through the annular driving mechanism therefor, and rests upon the inner edge of detachable driving or traction ring section 43, which edge may be knurled if so desired, although the knurling is not necessary. If the frame 31, 32 is adjusted, so that the plane of the driving ring is exactly perpendicular in

a horizontal plane, to the longitudinal axis of the pipe, then there will only be a point contact between the ring and the pipe, and rotation of the ring will only result in rotary movement of the pipe, without longitudinal movement being imparted thereto. Angular adjustment of the frame 31, 32, will result in the inner edge of ring section 43 contacting and supporting the under-surface of the pipe along an extended arc extending in the direction of the arc of the pipe, as is shown more clearly in Fig. 3. Rotation of the driving ring will, then, result in a longitudinal movement as well as a rotary movement being imparted to the pipe; the ratio between such movements being determined by the angular setting of the driving mechanism. Roll 3 is adjusted so that strip 7 leads off substantially parallel to the plane of the driving ring, as is shown in Figure 2.

Because contact between the pipe and the driving ring is over an extended arc, a positive traction drive obtains. For any given size pipe and ring section 43, this extended contact will obtain up to a certain point. Beyond such point, further movement of the frame 31, 32 will result in the pipe being lifted out of line contact with the traction or driving ring. Therefore, should it be desired to adjust beyond such point, so as to increase the linear speed of the pipe, a ring section 43 having a greater internal diameter should be substituted. This can be readily done by removing fastening means 46, and substituting the different size ring section 43 for the one already in place. In actual practice, the proper size ring section 43 can be selected for pipes varying in diameter within a predetermined range; and such section will provide for all practical ratios of longitudinal and rotary movements. It is only when it is desired to wrap pipe of a diameter outside of such range that a new ring section has to be substituted. Ring sections 43 of varying internal diameters can be provided with the machine; and the proper size can be selected for use with the size of pipe to be wrapped.

The weight of the pipe alone is sufficient to cause it to rest firmly in tractive engagement with the inner edge of driving ring section 43. However, to insure such engagement, spring pressed rollers are, preferably, provided to press the pipe against the inner edge of ring section 43. The rollers 66 (Fig. 1) are journaled in forks 67 secured to rods 68. Each rod 68 is slidably mounted in an externally threaded sleeve 69; also, each rod 68 is journaled in sleeve 69 and has its axis slightly offset with respect to the journal axis of the roller to provide a caster effect for the roller. Thus, the rollers 66 can automatically assume any position in compliance with the movements of the pipe. A spring 71 is interposed between each sleeve 69 and each fork 67, to urge the roller into contact with the pipe. Preferably, a sleeve 69 provided at each side of the frame 31, 32; and each sleeve is threaded in an end of cross arm 72 secured to the upper frame section 32 by means of screw 73 (Fig. 4). Because of the threaded mounting of sleeves 69, the pressure on springs 71 can be adjusted by turning of the sleeves. To effect simultaneous adjustment of spring pressure, sleeves 69 are connected for movement together by chain 74 (Figs. 1 and 2) engaging sprockets 76 on the sleeves; and a handwheel 77 on one of the sleeves enables turning thereof to the desired position.

In the modification of the driving or feeding mechanism disclosed in Figs. 6 and 7, the prin-

ciple of construction is the same as that already described, except that two driving units are employed in tandem and in staggered relationship. To designate the parts of each driving unit, which are the same as that for the one unit disclosed in Figs. 1 through 5, the same reference characters are employed. A spring pressed caster roller 78 is, preferably, positioned between the driving units of Figs. 6 and 7, and is slidably and rotatably mounted, by rod 79 and threaded sleeve 80, on cross arm 81 which is secured to the frame of each unit by studs 82. Arm 81 is journaled about studs 82; each of which studs lies in the journal axis about which the frames 31, 32 are angularly adjustable, so that adjustment of the frames can be accomplished without removing arm 81.

Although it is preferred that the inner edge of the driving or traction ring section 43 have an unbroken surface, or contact arc portion in order to provide for maximum surface traction with the pipe for a given length of arc, this is not necessary. Figs. 8 and 9 depict a modification in which the driving ring and, consequently, contact arc are composed of a plurality of separate members 86 mounted on the rotatable ring part 41. Members 86 project radially and are, preferably, radially adjustable to enable adjustment of the internal diameter of the traction ring which members 86 form. For the latter purpose, ring part 41 has a plurality of radial slots 87 communicating with radial grooves 88 in which members 86 are seated. Each member 86 is held in adjusted position by bolts 89 passing through the member and through the slot 87; nuts 90 securing the bolts against movement. In order that each of members 86 can be properly positioned readily so that the inner ends of the members can form a true circle, ring part 41 is preferably provided with a series of indicating lines 91 adjacent each member 86; and a complementary line 92 is provided on each member 86. Thus, by proper matching of all lines 92 with a selected line in lines 91, the adjustment of members 86 can be accurately accomplished.

Fig. 10 illustrates a further modified construction, in which the inner edge of ring part 43 is formed of traction enhancing material, such as rubber. The inner edge of ring part 43 is provided with an annular groove in which is held the rubber ring 95.

The provision of the resilient rubber ring is particularly desirable for engagement with objects coated with frangible material, such as enamel, inasmuch as the rubber ring will preclude scratching or chipping of such material.

From the preceding description, it is seen that I have provided a driving mechanism for supporting and feeding an arcuately shaped object with a combined rotary and longitudinal movement, which is of simple construction, and is therefore easy and economical to build. The annular driving means, which is of larger diameter than the diameter of the object to be driven, when set at an angle with respect to the axis of the object, has an effective arc contact with the object over a large area to provide for positive traction propulsion of the object. The length of arc contact with the object can be controlled by adjusting the angular position of the driving means with respect to the axis of the object. Since the driving means has contact with the object over an extended area, the object can be driven without application of pressure on the driving means, as is necessary with respect to the roller type of drive, characterized by opposed arc contact.

It is, therefore, seen that a principle of my invention also lies in a novel method of propelling the object, namely that of employing annular driving means surrounding and supporting the object, and positioning the driving means in such manner with respect to the object as to provide for effective arc contact between the driving means and the object.

I claim:

10. 1. Mechanism for imparting a combined rotary and longitudinal movement to a preformed object, comprising annular object supporting means rotatable about an axis and through which the object is adapted to pass, and means for mounting said annular means at an angle with respect to the axis of said object.
20. 2. Mechanism for imparting a combined rotary and longitudinal movement to a substantially cylindrically shaped preformed object, comprising a rotatable ring having inner means adapted to contact and support said object along an arc, and means for mounting said ring at an angle with respect to the axis of said object.
30. 3. Mechanism for imparting a combined rotary and longitudinal movement to a substantially cylindrically shaped preformed object, comprising annular means having an inner surface adapted to contact and support said object along an arc extending in the direction of the arc of said object, means for mounting said means for rotation in a plane disposed at an angle to the axis of said object, and means for effecting rotation of said annular means.
35. 4. Mechanism for imparting a combined rotary and longitudinal movement to a substantially cylindrically shaped preformed object, comprising a rotatable ring the inner edge of which is adapted to support said object along an extended arc, and means for mounting said ring at an angle with respect to the axis of said object.
45. 5. Mechanism for imparting a combined rotary and longitudinal movement to an object, comprising an annular member rotatable about an axis, a plurality of object-contacting members, means for mounting said object-contacting members for radial adjustment on said annular member to define a selected size of traction arc for said object, and means for mounting said annular member at an angle with respect to the axis of said object.
55. 6. Mechanism for imparting a combined rotary and longitudinal movement to a preformed object, comprising an annular object supporting member rotatable about an axis and through which the object is adapted to pass, a ring of resilient traction enhancing material secured for rotation with said member and adapted to contact said object along an extended arc, and means for mounting said member at an angle with respect to the axis of said object.
65. 7. Mechanism for imparting a combined rotary and longitudinal movement to a substantially cylindrically shaped preformed object, comprising annular means adapted to surround said object and carry the entire weight of the portion of the object surrounded thereby, means for mounting said annular means at an angle with respect to said object, and means for rotating said annular means about its center.
75. 8. In a pipe wrapping apparatus, annular means adapted to surround and to support said pipe along an extended arc and disposed at an angle with respect to the axis of said pipe, and means for rotating said annular means to feed

the pipe with a combined rotary and longitudinal movement.

9. Mechanism for imparting a combined rotary and longitudinal movement to a preformed object, including annular supporting and driving means adapted to surround said object, and disposed in a plane at an angle to the direction of longitudinal movement of said object.

10. Mechanism for imparting a combined rotary and longitudinal movement to a preformed object, including annular driving means adapted to support and surround said object and disposed in a plane at an angle to the direction of longitudinal movement of said object, said annular means having a traction arc contact with said object.

11. Mechanism for imparting a combined rotary and longitudinal movement to a cylindrically shaped preformed object, including annular driving means of larger diameter than that of said object and adapted to surround and support said object, said driving means being disposed in a plane at an angle to the direction of longitudinal movement of said object so as to have arc contact with said object.

12. Mechanism for imparting a combined rotary and longitudinal movement to a preformed object, including an annular driving member through which the object can pass and adapted to support the entire weight of the portion of the object passing therethrough, said annular member being disposed in a plane at an angle to the direction of longitudinal movement of said object.

13. Mechanism for imparting a combined rotary and longitudinal movement to a preformed object, including a driving ring through which the object can pass and adapted to support the entire weight of the portion of the object passing therethrough, said ring being disposed in a plane at an angle to the direction of longitudinal movement of said object and having an edge formed to provide tractive engagement with said object.

14. Mechanism for imparting a combined rotary and longitudinal movement to a cylindrically shaped preformed object, comprising a rotatable annular member through which the object can pass and serving solely to propel and support said object, and means for mounting said member for adjustment about an axis perpendicular to the direction of longitudinal movement of said object to enable positioning of said member at a selected angle with respect to said direction.

15. Mechanism for imparting a combined rotary and longitudinal movement to a cylindrically shaped preformed object, comprising a rotatable annular member through which the object can pass and serving solely to propel and support said object, said member being disposed at an angle with respect to the direction of longitudinal movement of said object and being adapted to have arc contact with an under portion of said object, and yieldable means for engaging an opposite portion of said object to cooperate in maintaining said arc contact.

16. Mechanism for imparting a combined rotary and longitudinal movement to a cylindrically shaped preformed object, comprising a rotatable annular member through which the object can pass and serving to propel said object and to support the entire weight of the portion of the object passing therethrough, said member having a knurled edge to provide tractive engagement with said object, yieldable means engageable

with said object to cooperate in maintaining said tractional engagement, and means for mounting said member for adjustment about an axis perpendicular to the direction of longitudinal movement of said object to enable positioning of said member at a selected angle with respect to the axis of said object.

17. Mechanism for imparting a combined rotary and longitudinal movement to a cylindrical-

ly shaped preformed object, comprising a rotatable annular driving unit through which the object can pass and constructed to have arc contact with and support said object only along one side of said object, said annular unit being disposed at an angle to the direction of longitudinal movement of said object. 5

WILLIAM F. FOCHA.
